DESIGN FOR A PIANO

George Laurence Miller, Philadelphia, Pa., assignor to Lester Piano Company, a corporation of Pennsylvania

Application July 1, 1935, Serial No. 57,478

Term of patent 7 years

To all whom it may concern:

Be it known that I, George Laurence Miller, a citizen of the United States, residing in Philadelphia, in the county of Philadelphia and State of Pennsylvania, have invented a new, original, and ornamental Design for a Piano, of which the following is a specification, reference being had to the accompanying drawing, forming part thereof.

The figure is a perspective view of a piano showing my new design.

I claim:

The ornamental design for a piano, substantially as shown.

In testimony whereof, I have hereunto signed my name this 29th day of June, A. D., 1935.

GEORGE LAURENCE MILLER.
